UNITED STATES PATENT OFFICE

HERMAN C. CAPPEL AND OTIS C. GROSS, OF DOVER, OHIO, ASSIGNEES TO GREER STEEL COMPANY, OF DOVER, OHIO, A CORPORATION OF WEST VIRGINIA

ANNEALING CONTAINER

Application filed May 9, 1929. Serial No. 361,680.

The invention relates to the annealing of strips of sheet metal in coils or bundles and more particularly to an improved carriage and container for enclosing the coils during the annealing operation, and to an improved annealing practice.

In the annealing of coiled sheet strips, it is now common practice to stack the coils one upon another upon an annealing carriage 10 or base, usually about four or five stacks of the coils being placed upon a base and covered with a single annealing box the carriage or base being then moved into an annealing furnace.

Under this old method of annealing, the furnace temperature is about 1600 degrees F. and thirty-six to forty-two hours is required for each operation.

Because of the size of these annealing 20 boxes, the walls must be of considerable thickness to properly reinforce the same against the temperatures to which they are subjected and it is customary to form these annealing boxes of cast steel or the like.

This extreme wall thickness of the annealing box requires that the annealing furnace be operated at a very high temperature in order that the heat penetrates the annealing box and brings the coiled strips to the proper 30 temperature.

This extreme temperature quickly burns out the lining of the annealing furnace and also rapidly deteriorates the annealing box, the average life of such annealing boxes being from fifty to eighty fires. This extreme heat frequently causes the coiled sheets to stick together, thus causing a loss in the annealing operation.

The object of the present improvement is 40 to provide an improved annealing pot or container comprising an individual container for each stack of coiled strips. Thus, instead of one annealing box to cover eight stacks of coils upon a carriage or base as is customary at present, with the improved apparatus eight individual annealing pots or containers will be placed upon each carriage or base, a stack of coiled strips being piled within each individual container.

The improved container is formed of rolled

plates or the like formed into cylinder shape, open at the lower end and closed at the upper end by a head preferably concaved at its center to compensate for expansion and contraction under changing temperatures, and provided with an eye or the like by means of which the container may be placed upon or lifted from the carriage or base. 55

With the use of this improved container, the furnace temperature is not nearly as high as required with the old method, the temperature being about 1350 degrees F. at the top and 1250 degrees at the bottom at the end of the operation. 60

Owing to the fact that each individual pot or container is substantially filled with coils, it has been found by experience that it is much easier to control and regulate the temperature therein and when the coils are ready to come out of the furnace there is a difference of only forty to sixty degrees F. between the top and bottom temperatures within the pot. 70

Under this new method of annealing, only eighteen to twenty-four hours is required as 75 compared with thirty-six to forty-two hours under the old method and owing to the reduced annealing time, ten tons of coiled strips may be annealed in eighteen to twenty-four hours whereas thirty-six to forty-two hours 80 was required to anneal three tons under the old method.

The cost of the new apparatus is less than half of the cost of the old apparatus and the life of the new apparatus is considerably 85 longer. Annealing pots now in use, made in accordance with the invention, have already been used for over 200 fires and are still in good repair, whereas eighty fires was usually the maximum life of the old cast annealing boxes. 90

The lower temperature at which the furnace may be run when using the improved annealing containers greatly increases the life of the furnace lining and also cuts the fuel 95 consumption in half.

Where 695 pounds of coal per ton of strips annealed was used in annealing under the old method, 819 pounds per ton are used in the same furnaces to anneal coils in the improved 100

annealing containers. The increased tonnage per heat also materially reduces the labor cost and it has also been found that a superior grain structure is produced in the annealed strips.

5 An embodiment of the invention is illustrated in the accompanying drawings, in which—

10 Figure 1 is a plan view of the improved annealing carriage showing several of the annealing containers or pots placed in position thereon, parts being broken away for the purpose of illustration;

15 Fig. 2 a side elevation of the carriage; and

15 Fig. 3, an enlarged transverse sectional view through the carriage showing the individual annealing containers mounted thereon, one container being cut in section to illustrate the manner of stacking the coiled strips 20 therein.

20 Similar numerals refer to similar parts throughout the drawings.

The carriage or base indicated generally at 10 may be formed of cast steel or the like and provided upon its under side with the usual 25 depending longitudinal ribs 11 having the grooves 12 to receive the balls 13 whereby the carriage may be moved into or out of the furnace in the usual manner.

30 The usual upright flange 14 may be provided around the edge of the carriage or base and grooves 15 are preferably formed in the upper surface thereof to receive pipes 16 by means of which an inert gas may be introduced into the annealing containers.

35 The improved annealing container or pot may be formed of a rolled plate or the like of substantially cylindric shape as shown at 17, the overlapping edges being riveted or otherwise connected as indicated at 18.

40 A head 19 is fixed in the upper end of the cylindric body portion, having the depending annular flange 20 connected thereto, as by rivets 21, welding or otherwise, and preferably having the concaved central portion 22 in order to permit of expansion and contraction under changing temperatures.

45 An eye 23 may be attached to the head in order to receive a hook or the like for placing the container in position upon the carriage or base and removing it therefrom.

The apparatus as illustrated in the accompanying drawings is adapted for the annealing of eight stacks of coiled strips, the coils, indicated at 24, being stacked one upon another and positioned as indicated in the drawings.

50 An outlet 25, for the inert gas, is provided upon each of the pipes 16 in position to admit gas to the interior of each stack of coiled strips.

55 After the coils are thus stacked upon the carriage or base, the improved annealing containers or pots are placed in position around the coils, as shown in the drawings,

and sand or the like may be placed around the lower end of each container to form a seal between the same and the carriage.

60 In order to accommodate a thermocouple, a raised portion 26 may be formed upon the carriage or base to receive one of the annealing containers, the thermocouple 27 being inserted into a V-notch 28 in the periphery thereof, the wires 29 leading therefrom to a pyrometer.

65 After the coils and containers have been placed upon the carriage, as above described, the carriage is moved into the furnace and left there for the required time, after which it is withdrawn and the coils are allowed to cool within the containers for the proper period of time, after which the containers and annealed coils are removed from the carriage.

70 After the carriage, with the containers and coils thereon, has been withdrawn from the furnace, an inert gas is admitted to the pipes 16, during the cooling period, for the purpose of preventing oxidation of the sheets.

75 We claim:

1. An annealing container for a single 80 stack of coils and formed of a rolled plate having its edges overlapped and connected together, and a head connected to one end of said container, said head having a central concaved portion.

2. An annealing container for a single 85 stack of coils and formed of a rolled plate bent into cylindric shape and having its edges overlapped and connected together, and a head connected to one end of said container, said head having a central concaved portion.

3. Apparatus for annealing coils including 90 a carriage upon which a plurality of stacks of the coils are arranged to be placed, a container for each stack adapted to rest upon the carriage, the top surface of the carriage having grooves therein, and pipes located in said grooves and having outlets around each of which a stack of coils is adapted to be 95 placed.

4. Apparatus for annealing a plurality of 100 stacks of superposed coils including a carriage upon which the coils are to be stacked, and a container adapted to enclose each stack 105 of coils, said container being formed of a rolled plate bent into cylindric shape and having its edges overlapped and connected together, and a head having a concaved central portion connected to one end of the 110 container.

115 In testimony that we claim the above, we have hereunto subscribed our names.

HERMAN C. CAPPEL.

OTIS C. GROSS.
